UNITED STATES PATENT OFFICE.

ROY J. WENSLEY, OF EDGEWOOD, PENNSYLVANIA, ASSIGNOR TO WESTINGHOUSE ELECTRIC & MANUFACTURING COMPANY, A CORPORATION OF PENNSYLVANIA.

ELECTRICAL RELAY.

Application filed November 15, 1924. Serial No. 750,183.

My invention relates to electrical relays and particularly to relays of the telephone type.

One object of my invention is to provide an improved mechanical latching device for maintaining the armature of an electrical relay in an operated position when the coil of such relay is deenergized.

Another object of my invention is to provide simple and efficient means for releasing the armature of the relay from its mechanically latched position.

A still further object of my invention is to provide simple and efficient means for attaching my improved latching device to a relay of an ordinary type.

There are other objects of the invention which, together with the foregoing, will be described in the specification which is to follow, taken in conjunction with the accompanying drawing.

In practicing my invention, I provide a latch bar of L shape which may be attached to one end of the relay, the armature of which is to be maintained in a mechanically latched position. Another relay is disposed below the first relay, with its armature disposed in such manner that, when the relay coil is energized, it is adapted to engage and operate the latch bar attached to the other relay. In all other respects, the relays may be of a usual and well-known construction.

Referring now to the drawings,

Figure 1 is a side elevational view of my improved relay;

Fig. 2 is an end view of the same;

Fig. 3 is a perspective view, illustrating the manner in which the armature of the relay is held in operated position by the mechanical latching device, and

Fig. 4 is a circuit diagram, illustrating the manner in which my improved relay is operated.

In Fig. 1, the broken lines indicate the positions of the members when the relay is operated and the mechanical latching device is maintaining the armature of the relay in its operated position.

Referring now to Figs. 1, 2 and 3, relays 1 and 2 are of the usual type so far as their principal elements are concerned. The relay 1 is mounted upon a frame or heel piece 3 that is attached, by means of a screw 3^a, to a supporting plate 4. A metal piece 5, upon

are insulated from each other, is attached to the frame 3 by means of a screw 10. An armature 11 is movably mounted upon the heel piece 3 and is provided, at one end, with a non-conducting member 12 to engage and lift the corresponding end of the spring 6 when the relay coil is energized. The spring 8 is a back-stop spring for maintaining the spring 7 in the proper relationship with respect to the spring 6. The spring 9 merely constitutes the electrical connection for one terminal of the coil of the relay 1. The armature 11 is provided also with a non-conducting member 13 (Fig. 3) to cooperate with a second spring like that shown in Fig. 1, and disposed parallel to it in the same plane.

A metal plate 14 is attached to one end of the heel plate 3 by means of a screw 15. A latch bar 16 of L shape and of non-magnetic material, is mounted upon the metal plate 14 by means of a hinge 17.

The relay 2 is mounted upon a frame or heel piece 18 that is attached to the supporting plate 4 by means of a screw 19. A metal piece 20, carrying a spring 21, is attached to the frame 18 of the relay 2 by means of a screw 22. The spring 21 constitutes the electrical connection to one terminal of the coil of the relay 2. An armature 23, having a weighted end 24, is mounted in position on the heel piece 18 in such manner as to actuate the lower end of the latch bar 16, when operated.

The operation is as follows: When the coil of the relay 1 is energized, which may be effected by closing its circuit at 28 (Fig. 4), the armature 11 is actuated and the spring 6 is forced from engagement with the spring 7, whereby the contacts 30 and 31 are separated.

At this time, inasmuch as the armature 23 of the relay 2 is in the position shown in Fig. 1, the upper end of the latch bar 16 is permitted to swing beneath the corresponding end of the armature 11 into the position shown in the broken lines in Fig. 1. When the coil of the relay 1 is deenergized, the latch bar 16 is maintained in the position shown and, consequently, the contact members 30 and 31 remain separated.

To effect engagement of the contact members 30 and 31, it is necessary to energize the coil of the relay 2 by closing its circuit at 29. When the coil of the relay 2 is energized, the armature 23 is actuated to cause the

weighted end 24 to move the latch bar 16 into its normal position. The movement of the latch bar 16 permits the armature 11 of the relay 1 to be restored to normal position under the influence of the springs 6. When the 5 coil of the relay 2 is deenergized, gravity carries the armature 23 to its normal position.

In the drawing, only one set of break springs has been shown on the relay 1. However, it will be apparent that these may be 10 make, as well as break, springs and that there may be several sets of springs attached to the relay in a well-known manner.

My invention is not limited to the particular arrangement of the apparatus described, 15 but may be variously modified without departing from the spirit and scope thereof, as set forth in the appended claims.

I claim as my invention:

1. A relay comprising a core, a coil mounted on said core, a heel piece, means for fastening said core to said heel piece, an armature mounted on one end of said heel piece and actuated by said coil when it is energized, and a latching device mounted on the other 25 end of said heel piece for maintaining the armature of said relay in a predetermined position.

2. A relay comprising a core, a coil mounted on said core, a heel piece, means for fastening said core to said heel piece, an armature mounted on one end of said heel piece and disposed to be operated when the coil of said relay is energized, and a latching device mounted on the other end of said heel piece 35 for maintaining said armature in operated position after said coil has been deenergized.

3. A switching device comprising a relay, an armature arranged at one end of said relay to be operated when said relay is energized, a latching device of angular form 40 mounted on the end of said relay opposite from said armature for maintaining said armature in operated position after the deenergization of said relay, and means for releasing said armature.

4. A switching device comprising a relay, an armature carried at one end of said relay to be operated when said relay is energized, a latching device of angular form mounted on the end of said relay opposite from said armature for maintaining said armature in operated position after the deenergization of said relay, and electromagnetic means for actuating said device to release said armature. 55

5. A switching device comprising a relay, an armature on one end of said relay to be operated thereby when the relay is energized, a second relay, a latching device mounted on the end of said first relay opposite from 60 said armature for maintaining the armature in operated position after the deenergization of said relay, and means controlled by said second relay for releasing the armature of said first relay. 65

6. A switching device comprising a relay, an armature at one end of said relay to be operated thereby when the relay is energized, a second relay, a latching device mounted on the end of said first relay opposite from said 70 armature for maintaining said armature in operated position after the deenergization of said relay, and means controlled by the second relay for actuating said latching device to permit the release of the armature of the 75 first relay.

7. A switching device comprising a relay, an armature carried on one end of said relay to be operated thereby when the relay is energized, a second relay positioned adjacent 80 said first relay, a latching device carried on the end of said first relay opposite from said armature for latching said armature in operated position, and means controlled by said second relay for releasing the armature of 85 said first relay.

In testimony whereof, I have hereunto subscribed my name this 5th day of November, 1924.

ROY J. WENSLEY.
